DESIGN FOR A GLOVE

Samuel Starr, Gloversville, N. Y.

Application January 23, 1939, Serial No. 82,539

Term of patent 7 years

To all whom it may concern:

Be it known that I, Samuel Starr, a citizen of the United States, residing at Gloversville, in the county of Fulton and State of New York, have invented a new, original, and ornamental Design for a Glove, of which the following is a specification, reference being had to the accompanying drawing, forming a part thereof.

Figure 1 is a plan view of the back of a glove showing my design.

Figure 2 is a plan view of the front of the

glove shown in Fig. 1 with a corner of the palm portion upturned.

The characteristic feature of my design resides in the downwardly and outwardly flaring corner of the wrist portion in combination with the downwardly tapering beading on the side opening of the glove as shown.

I claim:

The ornamental design for a glove, as shown and described.

SAMUEL STARR.
